UNITED STATES PATENT OFFICE.

ARTHUR S. E. METCALF, OF AMBERG, WISCONSIN.

COMBINED SHEARS AND KNIFE.

SPECIFICATION forming part of Letters Patent No. 631,403, dated August 22, 1899.

Application filed May 31, 1899. Serial No. 718,849. (No model.)

To all whom it may concern:

Be it known that I, ARTHUR S. E. METCALF, a citizen of the United States, residing at Amberg, in the county of Marinette and State of Wisconsin, have invented a new and useful Combined Shears and Knife, of which the following is a specification.

This invention relates to cutlery; and it has for its object to provide a combined shears and knife the elements of which are adapted to be folded into and out of their operative position and in which the knife is independent of the blades of the shears, enabling the formation of proper cutting edges on the knife and shears, one of said shear-blades having, moreover, a file upon its rear edge.

A further object of my invention is to provide a new and efficient arrangement of stop-springs for holding the foldable elements in their adjusted positions.

The invention consists of two handle elements pivotally connected, and upon the pivot of these elements are rotatably mounted two shear-blades and a knife-blade, said blades having individual stop-springs, the fixed ends of which are passed through openings in their respective handles to hold them immovably.

In the drawings forming a portion of this specification, and in which like characters of reference designate similar parts in the several views, Figure 1 is a perspective view of my implement with the shear-blades in opposite positions and open. Fig. 2 is a perspective view of my implement with the knife-blade 35 distended and the shear-blades and handles closely folded. Fig. 3 is an elevation showing the handles separated and the cutting-blades extending at different angles intermediate their folded and unfolded positions. Fig. 4 is a view showing the handle element which carries both the knife-blade and one of the shear-blades.

Referring now to the drawings, in operating in accordance with my invention I form two similar handle elements 7 and 20, having loops 5 at their rear ends for the reception of the thumb and finger or fingers of the operator. One of the handle elements 7 has a perforation adjacent its forward end, through which is passed a pivot-pin 9, having mounted thereon adjacent the face of the handle a knife-blade 10, at the rear end of the back of

which is formed a recess adapted to receive the adjacent end of a stop-spring 11, having a perforated lug 12, through which is passed 55 a pin 13, engaging the handle 7 and forming a means of attachment of the spring 11 thereto. The rear end of spring 11 extends through a recess 14, formed in the adjacent edge of the handle 7, in which recess it is held in a 60 manner to be presently described. The operation of the spring 11, in connection with the blade 10, is the same as in an ordinary pocket-knife and is well understood.

Mounted upon the pivot-pin 9 is a shear-blade 15, having at the end of its rear edge a recess 16, in which is seated the free end of a stop-spring 17, having a perforated lug 18, through the medium of which perforation it is mounted upon the pin 13, said spring passing 70 into the recess 14 and having its end disposed between the adjacent end of spring 11 and the end wall 19 of said recess. The springs 11 and 17 conform to the outline of the adjacent edge of the handle 7, and the extremities of the ends lying in the recess 14 are dressed off flush with the outer surface of the handle. In conformity with the well-known operation of stop-springs in pocket-knives the springs 11 and 17 in bearing against 80 the adjacent shoulders of the slots in the rear edges of their respective blades prevent the backward bending or movement of their blades and at the same time hold said blades against falling forwardly and also against accidental unfolding. Thus far it will be readily seen that either of the blades 10 and 15 may be extended to aline with the handle 7.

Upon the pin 9 is pivotally mounted the second handle element 20, which element is 90 similar in form and construction to the element 7, a second shear-blade 21 being also mounted upon the pin 9 intermediate the shear-blade 15 and the handle 20, the two shear-blades being in direct engagement and 95 so arranged that when they are distended they will coöperate after the manner of the usual construction of shears. A stop-spring 22 is connected with the handle 20 through the medium of a pin 23, passed through a lug 24 100 of said spring, the free end of the spring engaging a recess at the rear end of its respective shear-blade, the opposite end of the spring lying in a recess in the rear edge of the

- handle and engaging the end wall 25 of the latter. It will be understood that the end walls 19 and 25 of the recesses in the handles are beveled to prevent outward springing of the stop-springs. Thus it will be seen that when desired the knife-blade 10 may be folded against its handle element 7, as shown in Fig. 1 of the drawings, and that the shear-blades 15 and 21 will then be capable of operation in the manner of ordinary shears and may be given their correct cutting edges; also that, as shown in Fig. 2 of the drawings, when desired the shear-blades may be folded against their respective handles and that the knife-blade may be distended into a position ready for operation, said knife-blade having its proper form of cutting edge, which, as is well known, is entirely different from the cutting edge of a shear-blade.
- 20 It will be readily understood that I may construct my device of any dimensions and that I may vary the general style and appearance thereof without departing from the spirit of my invention.
- 25 Having thus described the invention, what is claimed is—
1. A device of the class described comprising handles pivotally connected, shear-blades pivoted to said handles, and a knife-blade mounted upon the pivot of the first-named blades and adapted to be distended with respect to the handles and interchangeably with the shear-blades.
  2. A device of the class described comprising

handles pivotally connected, shear-blades 35 pivotally mounted upon the pivot of said handles and adapted to be folded thereagainst and distended therefrom, and a knife-blade mounted upon said pivot and adapted to be folded against and distended from said handles interchangeably with the shear-blades. 40

3. The combination with a handle having a recess formed transversely thereof, of a blade pivoted in said handle, and a stop-spring carried by the handle, engaging said blade, 45 and having one end bent to lie in said recess.

4. The combination with two handles pivotally connected, of two shear-blades mutually adjacent and mounted upon the pivot of said handles, a knife-blade mounted also upon said pivot, and a stop-spring for each of said blades and adapted to hold them at different points in their pivotal movement.

5. The combination with a handle having a transverse recess therein, and a resultant 55 end shoulder, of a plurality of blades pivotally connected with the handle, a stop-spring for each blade, the ends of said springs being bent to lie in said recess, one upon another, the adjacent spring engaging said end shoulder to hold the springs therein.

In testimony that I claim the foregoing as my own I have hereto affixed my signature in the presence of two witnesses.

ARTHUR S. E. METCALF.
